CUFF-LINK

Jakob Sanger, Vienna, Austria

Application March 8, 1935, Serial No. 10,066
In France March 14, 1934

6 Claims. (Cl. 24—102)

It is known to connect the plates of cuff-links with their connecting arms and to interconnect these arms in such a manner that the parts are capable of moving relatively to one another. 5 Hinge joints arranged either only between the plates and their arms or only between the arms themselves are employed as connecting members. These joints, as is known, allow the arms or the plates to swing only in one and the same plane, 10 whereas the other connections, that is in the first instance between the arms and in the second instance between the plates and their arms, are constructed like eyes so that the arms or the plates are free to swing in all directions. Thus, 15 the parts of the cuff-link have ample latitude of movement, which is undesirable and prevents a uniform holding together of the edges of the cuff.

This invention relates to a cuff-link, in which 20 both the connection between each plate and its arm and also that between the arms are constructed as hinge joints and either all these hinge joints or at least those between the plates and their arms are equipped with spring detent means 25 which automatically lock the connected parts either in their relative extreme positions or at least in their closed position.

Two embodiments of the invention are illustrated by way of example in the accompanying 30 drawing in which:—

Fig. 1 shows in side elevation a cuff-link in 35 opened out position.

Fig. 2 is a plan view of Fig. 1.

Fig. 3 is a side elevation of the link in its intermediate position.

Fig. 4 shows the link in side elevation in closed 40 position.

Fig. 5 shows a hinge joint with arresting means in section on line V—V of Fig. 2.

Fig. 6 shows a simplified form of construction 45 in side elevation.

Fig. 7 is a cross section on line VII—VII of Fig. 4.

The cuff-link consists of two plates 1 and 2, 50 designed to bear against the outer side of the cuffs and each having on its inner side at one end a prismatic hinge body 5 with pins 4a projecting laterally one from each side of the hinge body. A connecting arm 4 is hingedly mounted at one end on the pins 4a of each of the hinge bodies 5, the other end of the arms 4 being hinged 55 on pins of a middle prismatic hinge body 6. The connecting arms 4 consist of plates of resilient material of a width preferably corresponding to but in any case not exceeding the length of the link holes in the cuffs. Tongues 9, 10 are formed 60 in the arms 4 by slots 4c, and coact with the prismatic faces of the hinge bodies 5 and 6 respectively and thus constitutes detents for arresting the parts connected by the hinge joints in

their two extreme initial positions as illustrated in Fig. 5.

For the purpose of closing, the cuff-link, after it has been inserted in the cuff holes, is first brought from the position illustrated in Fig. 1 5 into the intermediate position shown in Fig. 3 by swinging the arms 4 in the direction of the arrow x, and then into its closing position by swinging the plates 1, 2 in the direction of the arrow y, in which position the material of the cuff 11 is 10 clamped between the parts 1, 4 and 2, 4 respectively. The free ends of the plates 1 and 2 are then directed towards one another so that the cuff is additionally held together near its outer edges. 15

The simplified form of construction illustrated in Fig. 6 differs from that above described in that the inner ends of the arms 4 are merely connected by means of a hinge pin 12 so that this middle joint has no arresting means. This 20 presents the advantage that the joint 12, when the link is in closed position, can open slightly and consequently only the outermost edges of the cuff are held together. 25

The freedom of oscillation of the hinge joints 25 is limited in both forms of construction so that the link can only be folded in M-shape.

I claim:—

1. A cuff-link, comprising in combination two plates, hinges one on the under side of each of 30 said plates, two arms each mounted at one end on one of said hinges, a hinge joint interconnecting the other end of said arms, and spring detent means at least at the hinges connecting said plates with said arms and adapted to automatically lock the above interconnected parts at least in their closed position.

2. In a cuff-link as specified in claim 1 means for limited swinging movement of said hinges 40 so that the link can only be folded in M-shape.

3. A cuff-link as specified in claim 1, in which the hinges between the plates and the arms are arranged outside the middle of the plates.

4. A cuff-link as specified in claim 1, in which the hinges between the plates and the arms are 45 arranged at one edge of the plates.

5. A cuff-link as specified in claim 1, in which the hinges between the plates and the arms are arranged one near one end of each plate and the ends of the plates remote from the hinges are 50 curved and adapted to press against the outer side of the cuff when the link is in closed position.

6. A cuff-link as specified in claim 1, in which the arms each consist of a plate of a width not exceeding the length of the button hole in the 55 cuff, said plate having longitudinal slots dividing the plate into resilient tongues and said spring detent means consisting of blocks at the hinges adapted to coact with said resilient tongues.
